(57) **CLAIM**

The ornamental design for a handbag, as shown and described.

DESCRIPTION

FIG. 1 is a front perspective view of a handbag showing my handbag design;

FIG. 2 is a front view of the handbag shown in FIG. 1;
FIG. 3 is a rear view of the handbag shown in FIG. 1;
FIG. 4 is a right side view of the handbag shown in FIG. 1
(the left side view being a mirror image);

FIG. 5 is a bottom view of the handbag shown in FIG. 1;
FIG. 6 is a top view of the handbag shown in FIG. 1;
FIG. 7 is a front perspective view of an alternative embodiment of the handbag shown in FIG. 1; and,

FIG. 8 is a right side view of the alternative embodiment of the handbag shown in FIG. 7 (the left side view being a mirror image).

The broken line showing of the straps and buckles is for illustrative purposes only and forms no part of the claimed design.
